BRACELET BUCKLE

John Sand, Newark, N. J., assignor to Gemex
Company, a corporation of New Jersey

Application August 24, 1933, Serial No. 686,558

7 Claims. (Cl. 24—71)

This invention relates to a bracelet buckle; and has for one of its objects the provision of a buckle which may be contracted when the device is in folded position on the wrist of the 5 wearer.

Another object of the invention is the provision of a buckle which will allow of some elasticity in the encircling length of the bracelet, in order that the bracelet may snugly grip the arm. 10 Another object of the invention is the provision of a ratchet construction which will have two spaced sets of ratchet teeth with the catch bar extending between them so as to afford an even adjustment and secure holding of two slidably related parts.

Another object of the invention is the provision of an elastic extension and ratchet contraction of the parts in the buckle in which these parts will nest one within the other so as to enable 20 the buckle to fold into a more compact space than heretofore.

Another object of the invention is the provision of a construction of an elastically extensible device in which the housing for the spring which 25 affords the elasticity may be completed after assembly of the parts.

Another object of the invention is the provision of a construction of elastically extensible bracelet in which the sliding parts may be secured 30 and the spring housed in position without the use of solder for formulating the construction, the same being held in position by a folding or deflecting of the stock of the parts.

With these and other objects in view, the invention consists of certain novel features of construction, as will be more fully described, and particularly pointed out in the appended claims.

In the accompanying drawing:

Fig. 1 is a top plan view of the buckle shown 40 in partly contracted position with the links of the bracelet chain connected thereto.

Fig. 2 is a construction showing the sections in unfolded position and illustrating in dotted lines the spring which acts between the two sliding parts in one end section.

Fig. 3 is a view similar to Fig. 2 showing the opposite side of the sections.

Fig. 4 is a central sectional view of the sections in folded position.

Fig. 5 is a view similar to Fig. 4 illustrating the elastically urged part as being withdrawn from contracted position.

Fig. 6 is a view similar to Figs. 4 and 5 showing the sections in their initial positions of unfold-

ing and the disengagement of the ratchet teeth and the catch which engages therewith on the slidable part in one end section.

Fig. 7 is a sectional view on the line 7—7 of Fig. 4.

Fig. 8 is a perspective view of one of the parts of the elastically extensible end section.

Fig. 9 is a perspective view of the cover element which cooperates with the structure shown in Fig. 8.

Fig. 10 is a perspective view with one of the side walls broken away, illustrating the elastically extensible section in contracted position and with the parts of Figs. 8 and 9 assembled.

In the use of bracelets, particularly for wrist 15 watches and the like, it is desirable to provide so-called buckles consisting of a plurality of foldable sections which may be unfolded and disposed end to end, to enlarge the encircling length of the bracelet and in such a construction it is desirable 20 to provide sliding parts for one of the sections, which parts may be slid inwardly and caught in different ratchet teeth to hold the sliding parts in contracted position against extending, whereby the buckle may be diminished in its encircling length 25

after folded upon the wrist, and it is also desirable to provide an elastically extensible bracelet which I provide by utilizing an elastically extensible section in the buckle which may be extended either when the buckle is unfolded or 30

folded, to at either of these times permit of elastic extension and thus when folded to snugly grip the wrist and retain the bracelet in the position along the arm which it is desired the same will assume; and I have so arranged the elastically ex- 35

tensible section that the housing for the elastically extensible parts shall fit between the ratchet racks to afford a more compact relation of the sections when in folded position; and the following is a detailed description of the present embodiment of this invention illustrating the preferred 40

means by which these advantageous results may be accomplished:—

With reference to the drawing, I have disclosed 45 a buckle consisting of one end section 11, another end section 12, and an intermediate section 13 joining these two end sections and pivoted as at 14 and 15 to these end sections to permit them to swing one upon the other into substantially overlying relation and there be retained by 50 a suitable holding device, which will later be more fully described.

The end section 11 consists of two slidable parts, one part comprising a top plate 16 having sides 17 with inwardly-turned flanges 18 spaced from 55

the top plate 16, while the other part consists of a slide member 19 guided between the sides 17 and the inturned flanges 18 and the top wall 16, and is provided with a cross bar 20 at its outer end 5 to which one end of a chain 21 may be attached by a connecting link 22, and a cross bar 23 extending between the sides of the slide 19, which bar is provided with a flange 24 for engagement with the teeth of the two spaced racks to hold the 10 slide in differently adjusted positions.

The intermediate section 13 has flanges 25 along either side, which are cut to form a series of teeth 26 to be engaged by the catch 24 of the slide 19 to hold the slide in differently adjusted 15 positions when the sections are folded one over the other. These teeth are completely withdrawn from engagement with the catch 24 when the sections are unfolded or partially withdrawn from complete folded position, thus permitting free 20 sliding of the slide member 19 when such unfolding occurs.

The end section 12 also consists of two sliding parts, one part having a bottom wall 27 with sides 28 with this bottom wall cut out in its center 29 and provided with flanges 30 turned up along the sides of the cutout portion, as more clearly 25 illustrated in Fig. 8. The other part of the section 12 consists of a bottom wall 31 having side walls 32 with the edges of these side walls rolled 30 inwardly over the side walls 28, as shown at 33, see Fig. 10, so as to provide a guiding means to permit longitudinal extension and sliding of these 35 parts one on the other. The side wall 32 is provided with an ear 34 having an opening 35 thru which the pivot pin 15 extends for hinging this 40 part to the intermediate section 13. The bottom wall 31 is provided with a depressed trough 36 extending longitudinally centrally thereof, which registers with the cut-out portion 29 of the wall 27 when these two parts are in contracted or overlying position.

In assembling the section 12, the bottom walls 27 and 31 of the two parts are slid one into the other, the side walls 28 being guided in the rolled 45 edges 33 and a spring 37 is then placed in position with one end against the abutment 38 turned upwardly from the bottom of the trough 36 and extending into the cut-out portion 29 of this part. The spring is then contracted and a cover 50 39 is positioned with the laterally-extending edges 40 of its enlarged offset head 41 positioned in the notches 42 at the end of the flanges 30. This cover then extends between and along the 55 top edges of the flanges 30 over the spring while its end 43 extends downwardly into the trough 36 to form an abutment for the opposite end of the spring 37. This cover 39 is locked in position by a tongue 44 on the end of the bottom wall 27 which is rolled into the slot 45 in the 60 cover, as illustrated in Figs. 4, 5, 6 and 10. Thus this cover is securely held in position without the use of solder.

The opposite end link 46 of the bracelet chain is secured to the rolled eye 47 on the bottom 65 wall 27 of one part of the section 12, which permits this part to extend with relation to the intermediate section 13 and compress the spring as a pull is exerted to overcome the tension of the spring and which, upon release, will permit the spring to draw these sliding parts to a contracted position.

The housing of the spring necessitates the raising of the flanges 30 and the use of cover 39 to form a trough which will occupy space in the thickness of the assembled folded construction, 70

and in order that there may be a compact arrangement with all of the construction and mechanism herein shown, I have cut out the intermediate section as at 49 so as to permit this trough 50 to be housed therein and permit of a more compact buckle when the sections are held in their folded position by detents 51 on the section 12 snapping past the edges 52 of the flanges 15 10 18 by the resiliency of spreading of these parts due to the inherent resiliency of the stock. 10

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. In a bracelet buckle, a plurality of sections connected together, one end section having two parts slidably related, an intermediate section, cooperating means between said intermediate section and one of said parts consisting of a pawl and ratchet respectively on said part, and said intermediate section for retaining the same in adjusted position, the other end section also having two slidably related parts, and resilient means between said parts tending to move them into contracted position.

2. In a bracelet buckle, a plurality of sections hinged together, one end section having two parts slidably related, an intermediate section, cooperating means between said intermediate section and one of said parts consisting of a pawl and ratchet respectively on said part and intermediate section for retaining the same in adjusted position, the other end section also having two slidably related parts, and resilient means between said parts tending to move them into contracted position, said intermediate section being cut out in its middle portion and said resilient means partially housing in said cut out portion when said sections are in folded position.

3. In a bracelet buckle, a plurality of sections hinged together, one end section having two parts slidably related, an intermediate section, cooperating means between said intermediate section and one of said parts consisting of a pawl on one of said parts and ratchet consisting of spaced racks on said intermediate section for retaining the same in adjusted position, the other end section also having two slidably related parts, and resilient means between said parts tending to move them into contracted position, said intermediate section being cut out between said racks and said resilient means partially housing in said cut-out portion.

4. In a bracelet buckle, a plurality of sections connected together, one end section having two slidably related parts, one part having a depressed trough with an abutment at one end, the other part having spaced flanges, a cover piece secured in position to bridge the space between said flanges with one of its ends extending downwardly to provide an abutment, and a spring in said trough and between said flanges and acting between said abutments.

5. In a bracelet buckle, a plurality of sections hinged together, one end section having two slidably related parts, one part having a depressed trough with an abutment at one end, the other part having spaced flanges, a cover piece secured in position to bridge the space between said flanges with one of its ends extending down- 75

wardly to provide an abutment, a spring in said trough and between said flanges and acting between said abutments, and a portion of said part bent back upon itself and locking said cover in position.

6. In a bracelet buckle, a plurality of sections hinged together, one end section having two slidably related parts, one part having a depressed trough with an abutment at one end, the other part having spaced flanges having an undercut at one end, a cover piece secured in position to bridge the space between said flanges and having a portion of one end held in said undercut and with its other end extending downwardly to provide an abutment, and a spring in said trough and between said flanges and acting between said abutments.

7. In a bracelet buckle, a plurality of sections hinged together, one end section having two slidably related parts, one part having a depressed trough with an abutment at one end, the other part having spaced flanges having an undercut at one end, a cover piece secured in position to bridge the space between said flanges and having a portion of one end held in said undercut and with its other end extending downwardly to provide an abutment, and a spring in said trough and between said flanges and acting between said abutments, and a portion of said part bent back upon itself and engaging said cover adjacent said abutment for locking said cover in position.
